UNITED STATES PATENT OFFICE.

JOHN W. BERWICK, OF BROOKLYN, NEW YORK.

REPORT-RECORD.

1,112,428.

Specification of Letters Patent.

Patented Oct. 6, 1914.

Application filed May 2, 1913. Serial No. 765,116.

To all whom it may concern:

Be it known that I, JOHN W. BERWICK, a subject of the King of Great Britain, and a citizen of the Dominion of Canada, residing at Brooklyn, county of Kings, State of New York, have invented certain new and useful Improvements in Report-Records, of which the following is a clear, full, and exact description.

- 10 This invention relates to report sheets intended to be used in conducting a business. It is particularly useful when used in connection with a business requiring the entry of considerable data upon the report sheets.
- 15 A general object of the invention is to provide means for facilitating the entry and carrying forward of the figures relating to the business and especially with a view to enabling the result of the business during a 20 considerable period to be presented concisely and systematically.

A principal object of the invention is to provide a report sheet especially adapted to receive data resulting from the conduct of a 25 business during a more or less extended period of time, and arranged in such a way as to facilitate the systematic presentation of the entries therein.

A further object is to provide a report 30 sheet which is arranged so as to coöperate with the report sheet referred to above so that results or reports for short periods such as the daily or weekly results, can be readily tabulated or totaled upon the principal report sheets with a view to presenting the results of the business so that as far as possible the daily and weekly results are maintained together with the totals for the months or year.

40 The invention consists in the features, or combination of features of the report sheets to be set forth more fully hereinafter, while the broad scope of the invention will be pointed out in the appended claims.

45 In the drawings, Figure 1 is a view showing one of the main report sheets, that is, a sheet which covers a relatively long time period; and Fig. 2 is a view showing a plurality of the report sheets put together and 50 forming a report-book or record.

The report sheets to be described or their novel features may be employed in the conduct of businesses of different kinds. For the purpose of illustration, I have illustrated 55 the sheets as used in conducting a photographic developing and printing business.

When adapting the report sheets to such a business, I prefer to provide a plurality of main report sheets 1 which preferably cover a week in time. These sheets are entitled 60 "Weekly summary" and have a blank space 2 to show by whom the results or figures on the sheet have been totaled and other blanks 3 and 4 for the same general purpose. Each sheet may also include date blanks. Each of 65 these "weekly summary" sheets is preferably divided in a horizontal direction into different headings such as "Developing department," "Printing department," "Enlarging department," "Rackers," and under 70 these headings blank spaces are placed for names of employees operating in the different departments, and opposite each name line a number space may be provided to receive a number corresponding to the name of 75 the employee. At a suitable point on each of these sheets preferably at the lower right-hand corner, I provide a plurality of separable coupons 5 which are separated from each other by score lines as shown, and these 80 coupons have abbreviations such as "Jan.," "Feb.," "Mar.," etc., corresponding to the different months of the year and arranged in regular succession with spaces 6 and 7 before and after each month abbreviation. In 85 addition to this and preferably above the aforesaid coupons, I prefer to provide a plurality of detachable coupons 8 which are numbered consecutively from 1 to 5 and indicate the successive weeks which may occur 90 in a month, and these coupons have blank spaces to receive figures indicating the weekly sales from the department. The sheet may also include a plurality of detachable coupons 9 numbered consecutively and 95 indicating the different pay-days in the month and having blank spaces 10 to receive entries indicating the amount paid to employees or to be paid to employees on each pay-day, and the entries at this point may 100 also include other expenses and indicate the total weekly expense in the conducting of the business.

Below the different headings, each sheet 1 may be provided with the word "Totals" as 105 indicated at 11 and on this total line the totals for each week can be written for the different departments, and below this point sundry expenses may be placed in the space 12. Below the space 12 columns are provided for different purposes such as chemicals used, paper used, and columns indicat- 110

ing different sized prints made together with sundry expense blanks such as for salary total, etc. Preferably near the time period coupons, such as the month coupons 5, spaces 5 are provided for the entry of general expenses, such as rent, repairs, etc.

In order to facilitate the obtaining of the totals which are entered on this sheet, I provide a plurality of daily report sheets 13, 10 two of which are illustrated in Fig. 2 laid upon a plurality of the other weekly or monthly sheets. These report sheets 13 are preferably divided into headings corresponding to those of the report sheets 1, 15 namely, "Developing department," "Printing department," "Enlarging department" and under the printing department a row of numbers 14 are formed, said numbers corresponding to the individual numbers of the 20 different employees in the printing department. In the spaces under these numbers entries are made indicating the number of prints made by the different employees. These sheets 13 are divided by horizontal 25 score lines 15 into a plurality of detachable coupons 16, and these coupons indicate the days of the week in succession, which may be by the abbreviations as indicated "Mon.," "Tues.," etc. Each coupon presents blank 30 spaces running under the different headings and intended to receive entries relating to the different departments or headings.

The reports are entered daily upon the proper day line and in making up the complete report the coupons below the day line on which the entry is made are torn off, thus the line 17 indicates the lower edge of the Monday report. At the end of the week these daily report sheets are arranged in 35 order with the Saturday report sheet at the bottom so that they overlap each other in a step by step arrangement, each report exposing the day line to which it refers but not covering the day lines of any other report sheets. The totals for each week which are arrived at by adding up the vertical columns under the headings of the report sheets are placed on each weekly report sheet 1 and are then entered on the proper 40 coupons where spaces are provided for such figures, for instance in the spaces on the coupons 8 the amounts or results from the total weekly sales are entered. The expense amounts are carried along and entered on 45 the coupons 9; and in making up the report these coupons are detached below the points where the entries are made so that the upper sheets leave the coupons of the lower sheets exposed. On the weekly report sheet which 50 is at or about the end of the month, the entry of the profit or loss for the month may be made on one of the coupons 5. This particular weekly sheet should also receive all entries such as rent which are collectible or 55 payable monthly.

In Fig. 2 the report as to the months is illustrated as having continued through the month of May. On each finished monthly report sheet, the coupons below the name of the month where the entry is made are torn off so as to expose the next month. In this manner the data relating to the daily and weekly business is carried along and entered on the report sheets and kept in place so that it is readily available for inspection, and when the period of time covered amounts to a year, twelve of the weekly report sheets will also constitute monthly report sheets as well, and among other information, will give the sales or profits for the different so months exposed to view in succession at the lower right-hand corner of the sheet. The results of any particular week can be found by opening the report sheets or book at the proper point. In this way a very complete 85 report or record of all the principal transactions of the business is maintained, and totals may be made and carried along showing the results of business for each day or week or month; or any other divisions of time as 90 may be desired.

The weekly sales coupons 8 are preferably longer than the coupons 5 and are arranged so that when the unused lower coupons 8 are detached, all the portion of the sheet down to the lower margin is torn out. When the last (4th or 5th) weekly report is entered, this lower part is not removed but receives entries of monthly data such as for "rent" and "gas". By removing the lower part of the earlier week sheets in this way, the spaces for the items entered monthly (such as rent) are left exposed on the last weekly sheet for that month.

It is understood that the embodiment of 105 the invention described above is only one of the many embodiments or forms the invention may take, and I do not wish to be limited in the practice of my invention nor in the scope of my claims to the precise embodiment described above.

What I claim as new is:

1. A report record consisting of a plurality of sheets corresponding to different time periods and having spaces thereupon for the entry of data regarding the business to which said report record relates, said sheets having a plurality of detachable coupons bearing the names of said time periods arranged in regular chronological succession and arranged on said sheets so that the names of said time periods will be superposed upon each other when said sheets are superposed, whereby certain of the coupons of the upper sheets may be torn off to expose the corresponding coupons of the under sheets, said time period coupons having entries of figures thereupon representing the results in the different time periods.

2. A report record consisting of a plu-

rality of sheets corresponding to the different months of the year, said sheets having spaces for the entry of data regarding the business to which said report record relates, 5 said sheets having detachable coupons bearing the names of the months of the year arranged in regular chronological succession and arranged on same sheets so that coupons corresponding to the said months may 10 be superposed upon each other, whereby certain of the coupons of the upper sheets may be torn off to expose the corresponding coupons of the under sheets, said sheets further having a plurality of detachable coupons 15 numbered to correspond with the successive weeks of a month and arranged so as to be superposed upon each other.

3. A report record consisting of a plurality of sheets corresponding to the different 20 months of the year having headings for the entry of data regarding the business to which said report record relates, said sheets having a plurality of detachable coupons bearing the names of the months of the year 25 arranged in chronological succession and arranged so that the different monthly coupons are superposed upon the corresponding monthly coupons when the sheets are superposed upon each other, said monthly coupons 30 being arranged for the entry of results of the business for the different months, in combination with a second plurality of report sheets having a plurality of detachable coupons numbered in order and corresponding 35 to successive divisions of time less than a month, said last named report sheets having headings for the entry of data to align with and correspond with the headings for the data which is entered on said monthly 40 report sheets, said last named report sheets being disposed between said monthly report sheets, said second plurality of sheets being of less extent than the monthly sheets so as to leave said monthly coupons exposed.

45 4. A report record consisting of a plurality of monthly report sheets corresponding to the different months of the year, having similarly arranged headings thereupon for the entry of data regarding the business 50 to which said report record relates, said sheets having a plurality of detachable coupons bearing the names of the months of the year arranged in succession and adapted to become superposed upon each other when 55 said sheets are superposed, in combination with a plurality of daily report sheets arranged like the said monthly report sheets to receive data regarding the business to which said record relates, said daily report 60 sheets having a plurality of detachable coupons corresponding to the days of the week arranged in regular succession, said daily report sheets being substantially identical so that when superposed the corresponding 65 day coupons are superposed upon each other,

and being of less extent than said monthly report sheets so as to leave said monthly coupons exposed.

5. A report record consisting of a plurality of sheets corresponding to the different months of the year, having similarly arranged headings thereupon for the entry of data regarding the business to which said report record relates, said sheets having a plurality of detachable coupons bearing the 70 names of the months of the year arranged in the same order on all the sheets so as to become superposed upon each other when said sheets are superposed, in combination with a plurality of daily report sheets having headings like the said headings and arranged like the said headings on said monthly report sheets to receive data regarding the business to which said report record relates, said daily report sheets having a plurality of detachable coupons bearing the 75 names of the days of the week arranged in regular succession and in the same order on the different sheets, said daily report sheets being similar so that when superposed the corresponding day coupons are superposed upon each other, said monthly report sheets having a plurality of detachable coupons numbered in succession to correspond with the successive weeks of the 80 month and arranged to become superposed upon each other when said monthly report sheets are superposed, and bearing characters indicating the weekly results, said monthly coupons having characters indicating the monthly results.

6. A report record consisting of a plurality of sheets bearing the names of different time periods, said sheets having the same headings thereupon regarding the business to which said report record relates, said sheets having a plurality of detachable coupons corresponding to the said time periods and arranged in regular succession, and superposable upon each other when said sheets 105 are superposed, said sheets having characters indicating spaces for the entry of data regarding the business, and a plurality of report sheets covering shorter time periods having headings corresponding to and superposable upon the headings of said first named report sheets, said last named report sheets having a plurality of detachable coupons arranged in order corresponding to said shorter time periods, said coupons of 110 said first time period sheets and of said shorter time period sheets having characters indicating spaces to receive figures corresponding to the results for the different time periods.

7. A report sheet for conducting a business, corresponding to a time period, and having a plurality of detachable coupons corresponding to successive time periods arranged successively to receive entries of figures.

ures giving results for the corresponding time periods, in combination with a plurality of smaller second report sheets corresponding to shorter time periods; said second report sheets having a plurality of detachable coupons arranged in order to correspond with a succession of said shorter time periods; and having alining entries of data occurring in the transaction of the business, 10 said first named report sheets carrying the totals of the entries on said second report sheets exposed beyond the edge of said second report sheets.

8. A report sheet to be used in conducting 15 a business, corresponding to a month of the year, said report sheet having a plurality of detachable coupons bearing the names of

the months arranged in regular succession, to receive figures representing monthly results from the business, in combination with 20 a plurality of daily report sheets, all of said report sheets having corresponding headings correspondingly arranged, said daily report sheets having a plurality of detachable coupons bearing the names of the days 25 of the week arranged in regular succession thereupon, and having spaces for the entry of daily data respecting the business.

Signed at New York city, New York, this 1st day of May, 1913.

JOHN W. BERWICK.
